UNITED STATES PATENT OFFICE

117,349

DESIGN FOR A COMBINED DESK AND SAFE OR SIMILAR ARTICLE

Charles R. Davis, Rochester, N. Y.

Application April 12, 1939, Serial No. 84,375

Term of patent 14 years

To all whom it may concern:

Be it known that I, Charles R. Davis, a citizen of the United States, residing at Rochester, county of Monroe, State of New York, have invented a new, original, and ornamental Design for a Combined Desk and Safe or Similar Article, of which the following is a specification, reference being had to the accompanying drawing, forming part thereof.

The figure is a perspective view of the combined desk and safe or similar article, showing my design.

I claim:

The ornamental design for a combined desk and safe or similar article, substantially as shown.

CHARLES R. DAVIS.
